UNITED STATES PATENT OFFICE.

SOLOMON MEYER LEVY, OF CLEVELAND, OHIO.

DESIGN FOR A CURLING-IRON MEMBER.

SPECIFICATION forming part of Design No. 31,971, dated December 12, 1899.

Application filed November 16, 1899. Serial No. 737,245. Term of patent 7 years.

To all whom it may concern:

Be it known that I, SOLOMON MEYER LEVY, a citizen of the United States, residing in Cleveland, in the county of Cuyahoga and State of Ohio, have invented and produced a new and original Design for a Curling-Iron Member, of which the following is a specification, reference being had to the accompanying drawing, forming part thereof, and in which the single figure is a perspective elevation of my new design.

As shown in the drawing, the leading or material feature of the design consists in the appearance thereof as a whole or in the design in its entirety rather than in any special and distinguishing mark or peculiarity of any portion taken separately.

In this whole or entire design there are, however, constituent features which may be separately considered and go to make up the

complete design, the same being marked *a*, *b*, and *c*, respectively. Thus the feature *a* is distinctive and peculiar in its outline, being practically U-shaped, as seen in end view, and having ornamental recurved edges 2 and plain surfaces within and without. The opposite end *b* is barrel-shaped in design or figure, while the intermediate feature (indicated by *c*) is suggestive of the breech of a gun in outline and lends such an appearance to this part of the design especially.

What I claim is—

The design for a curling-iron member, substantially as herein shown and described.

Witness my hand to the foregoing specification this 10th day of November, 1899.

SOLOMON MEYER LEVY.

Witnesses:

H. T. FISHER,
R. B. MOSER.
